Application October 10, 1949, Serial No. 5,401

Term of patent 7 years

(Cl. D47—7)

To all whom it may concern:

Be it known that we, Shepard B. Schwartz and Robert D. Blum, Jr., citizens of the United States of America, residing at Nashville, in the county of Davidson and State of Tennessee, have invented a new, original, and ornamental Design for Sock or Similar Article, of which the following is a specification, reference being had to the accompanying drawing, forming a part thereof, wherein the single figure of the drawing is a side elevation of a sock or similar article, illustrating our new design.

The design shown in the drawing is applied to both sides of the sock or similar article.

We claim:

The ornamental design for a sock or similar article, as shown and described.

SHEPARD B. SCHWARTZ.
ROBERT D. BLUM, JR.
